SIGN CONSTRUCTION

John A. Henning, San Jose, Calif.

Application May 18, 1931, Serial No. 533,156

9 Claims. (Cl. 40—32)

This invention relates to a sign construction and particularly a construction in which a message as an advertising spread or slogan can be brought to the attention of the public or interested persons in a novel and attention holding manner.

The invention is particularly concerned with the provision of a sign to display a message of relatively great length without requiring the extensive, intricate electrical mechanisms heretofore utilized.

The invention is also concerned with certain improvements in sign construction which enable a sign to be provided of a relatively simple and inexpensive nature to display a message in a peculiarly distinctive and interest-attracting manner.

The invention possesses other advantageous features and objects, some of which, with the foregoing, will appear at length in the following wherein I have outlined the preferred form of the sign construction of my invention. In the drawings, accompanying and forming a part of this specification, I have illustrated the preferred form of sign construction of my invention but it is to be understood that other forms thereof can be adopted without departing from the invention.

In the drawings, Figure 1 is a front elevation of the sign construction shown in plan in Figure 34, the view being in right and left hand fragments.

Figure 2 is a plan view from the bottom of the sign, the view being partly in section.

Figure 3 is a section taken through a sign, generally along the line 3—3 of Figure 4.

Figure 4 is a plan view, partly in section, taken through a sign embodying the construction of my invention.

Figure 5 is a plan view of a portion of the message carrying medium or belt.

Figure 6 is a section through the medium or belt.

In its preferred form, the sign of my invention is characterized by the inclusion of a display portion which is adapted to be positioned so as to be plainly visible to public view. Over this portion, a message carrying medium is adapted to be moved so that a portion of its message is always on display. In accordance with my invention, I am enabled to provide a sign in which the total message length can be relatively great and in which various messages can be brought to the public attention, one after the other.

In the preferred form of the sign construction shown in the drawings, I have depicted all of the working mechanism of the sign as being included within a casing 5, while certain of the mechanism

is carried on an inner casing 6 which is movable relative to the casing 5. The casing 5, usually constructed of a suitable material as sheet iron, is open on one side. Over this open side a suitable frame 7, preferably of an ornamental nature, is positioned. Within the frame, a suitable transparent medium or means 8 such as a glass sheet is positioned through which the message is displayed. This medium or means can be either a plain glass or one having light diffusing or reflecting surfaces. The illumination of the message through the sheet 8 can be effected by any suitable means such as sunlight or by the use of artificial illuminating means as a plurality of electric globes 9 carried in sockets 11 mounted on the inner casing 6. Suitable light directing means as reflectors 12 are positioned about the globes 9 to direct the light therefrom onto the transparent glass 8 through the belt 14.

The length of the display portion of the sign construction is usually relatively short since the sign has been used with particular success in store windows or in store front illumination. However, in accordance with my invention, I am enabled to show a message of vastly greater length than that of the display length of the frame 7. Thus the message length is not limited to the length of the frame 7 nor is not confined or limited by the length of the sign itself.

In the preferred form of the invention I have secured this desirable result by providing a medium 14 for carrying the message continuously over a path which includes a display portion and another portion, preferably of a tortuous nature, thereby enabling the message to be very long. As a medium I preferably use an opaque and non-light transmitting belt of a flexible resilient nature. I have successfully used a belt of a packing material—that manufactured and sold by The Anchor Packing Company under the trade-mark "Hydrol", registry number 91,305.

The message to be conveyed is cut out of the body of the belt so that when the belt is positioned between the reflectors and lamps and the glass 8, light passes through the cut out portion of the belt and thus delineates the letters on the belt within the frame 7. The style of letter used and the manner of forming the message in the belt can be varied. I have successfully used a punch and formed the letters of a plurality of small holes as is shown in Figure 1.

There are several features in the use of this continuous belt that I believe to be particularly desirable and novel. Thus, that portion of the

inner casing corresponding to the frame 7 is provided with trackways 15 for the belt. These trackways are formed by fastening angle pieces 16 adjacent to the edges 17 of the casing, the trackways extending the length of the display portion of the casing and confining the edges of the belt.

The belt is circulated over a pair of wooden rollers 18 which are supported in the upper portion and in the bottom of the inner casing by roller bearings 21. The rollers 18 serve to guide the belt in its entrance into the trackways from the tortuous portion for movement over the display portion of the frame.

I have found that it is more advantageous to pull or draw the belt past the display portion rather than to force it thereover. Accordingly, I provide a pair of driving rolls 22 which are likewise suitably journaled in roller bearings 23 carried by the inner casing. These rolls are preferably positioned to cooperatively engage the belt as if passes between them, the rolls being of sponge rubber to engage the belt in a positive driving engagement.

The belt, which is engaged and is pulled by the rolls 22 over the display portion, is preferably forced directly out from between the rolls into a guide portion which I have indicated at 26 and which is formed by plates 27 and 28. These confine the belt for some little distance and ensure that it passes away from the rolls and cannot become wound around them. For this reason the plate 27 includes a portion 31 which is adapted to conform to the periphery of a roll very closely so that the belt cannot feed back around the roll while the plate 28 likewise includes a portion 32 which is adapted by its formation to prevent the belt from feeding back around the adjacent roll. Further, the plate 27 continues with an arcuate guide portion against which the belt is guided by a driven roller 33 so that the belt is forced on its way in a predetermined manner.

All the rolls are conveniently driven by an electric motor 24 likewise positioned on the inner casing and adapted to drive the several rolls at the correct speed through gearing, generally indicated at 25, and through the belt connection 34. The belt connection is desirable since it provides against tearing of the continuous message belt if it should happen to stick in the trackway as sometimes, though very infrequently, happens.

The motor is suspended from a bracket 36 on the casing and carries a fan 35 adapted to create a cooling air circulation through the several vents 37 so that the sign is maintained cool. It is to be noted that some of the vents are shrouded as at 40 so that light cannot pass therethrough to any considerable extent to other vents, and thus detract from the message.

Since the use of a very long belt carrying a long message or a succession of messages is advantageous, I preferably include means for receiving and returning that portion of the belt which is to be immediately shown in the display portion. I accordingly include a suitable reservoir generally indicated at 38 within the inner casing. This reservoir is formed by the confining walls 42 and 43 together with the guide walls 39 and 41 and the plates 27 and 28. The arrangement of these is such that the belt forms itself into a plurality of convolutions 44 jammed together in regular fashion so that the belt subsequently feeds out over the rollers 18 without mishap. A great length of belt can thus be disposed of very simply. This manner of disposition of the

belt within the reservoir is more advantageous than if the belt were wound about various mechanical means such as a plurality of rollers over which the belt is drawn. However, under some circumstances, it is desirable to employ such a device in place of the simple storage space, but only under the burden of increased expense and operating difficulties.

It has been previously mentioned that the working mechanism of the sign is carried on the inner casing 6. This is preferably arranged to slide relative to the enclosing casing 5 so that certain adjustments and visual effects can be secured. Thus

I include another light diffusing or refracting medium or means 47 on the inner casing 6 between the light source and the belt. The effect of the two light handling media is secured on the visible message. This effect, depending on the arrangement and relative positioning of the two and the style in which the message is cut out of the belt, can be varied to secure either a plain delineation of each letter, or other delineations of a startling brilliance, clarity and interest, attracting nature. Effects such as these are not possible with Neon and like illuminants, are achieved by this arrangement. When an adjustment of the two media, which is deemed satisfactory is secured, the casings 5 and 6 are locked in that position by screws 48 engaging lugs 49, on the inner casing.

When it is desired to change the belt, the connection shown in Figures 5 and 6 can be simply and quickly broken by an operator. Thus, by grasping opposite sections or ends 51 and 52 of the belt, and pulling the sections apart, hinge 53 separates. This hinge is formed by a first member 54 fastened by rivets 56 to section 51 and a like member 57 fastened to the other section 52 so that the cooperating and interlocking portions 58 engage. By sliding the two members relative to each other, the juncture can be broken. The hinge is a flexible nature and is only as thick as the belt. If desired, the various letters comprising the message can be formed separately and joined together by means of such connections, or various words, or combinations of words, can be made up in stock form and afterwards hinged together.

After the belt has been separated, an end of a replacement belt, carrying the new message desired, is attached to the old belt. The motor can then be used to draw the new belt into place. The previous belt will be forced from out of the machine and its place taken by the new belt which is carried through. The new belt hinge may then be made up and the sign placed in operation.

The sign is, of course, suitably wired, all the lamps preferably being in parallel and a fuse 61 being included. The motor and lamps are preferably furnished with current through the same connection to facilitate installing.

In the foregoing I believe that it will be apparent that I have devised a novel form and features of sign construction that make available a maximum efficiency of a very short advertising space, enabling a very long message, or a succession of messages, to be continuously and successively placed in view before the public in a novel, attractive and inexpensive manner. Thus, in a sign having a display front of some three feet in length I have been able to display messages of a total length of 35 to 50 feet. This display was secured in a manner that kept the public interest, because of the character and interest-attracting display of the message on the belt.

While the belt speed can be varied by changing

- the gearing or the motor speed, I have found a speed of about 60 feet per minute across the display front satisfactory. This is a matter of psychology, depending in part also on the message shown and the media used for refracting or diffusing the light through the belt. By adjusting the relative positions of the media, the belt and the speed of the belt different illuminations and portrayals of the message can be secured.
- 10 I claim:
1. In a sign including a relatively long flexible continuous message carrying belt, a display portion for showing only a portion of the message carried by the belt at one time, means for storing that portion of the belt not being displayed, means for pulling the belt over the display portion continuously, and a stationary curved guide member for directing the belt into the storage portion, said guide member having an end terminating adjacent the point where the belt leaves said pulling means and on which the belt travels for directing the belt into said storing means.
  2. In a sign, a display portion, a light refracting or diffusing medium positioned over the display portion, a continuous belt having a message therein adapted to be moved past the medium, means for illuminating the belt and the medium, and means for adjustably positioning the medium, belt and illuminating means to secure a desired illumination of the message in the belt.
  3. In a sign, a casing having a sign display portion, an endless belt of greater length than the display portion and adapted to be moved past the display portion, a chamber for storing the portion of the belt not being displayed, means directly adjacent an end of said display portion for pulling the belt past the display portion, and stationary guide members adjacent said belt pulling means forming a predetermined path for directing the belt in folds into said storage chamber, said guide members having ends terminating adjacent the point where the belt leaves said pulling means for directing the belt into said chamber without back winding thereof.
  4. In a sign, a display portion, spaced light refracting or diffusing media positioned over the display portion, a continuous belt having a message adapted to be moved past and between the media, means for illuminating the belt and media,
- and means for mounting the media for adjustment relative to each other.
5. In a sign, a display portion, spaced light refracting or diffusing media positioned over the display portion, a member having a message and between said media, means for illuminating the member and media, and means for mounting the media for adjustment relative to each other.
6. In a sign, a display portion, a light refracting or diffusing medium positioned over the display portion, a member having a message and spaced from the medium, means for illuminating the member and medium, and means for mounting the medium and member for adjustment relative to each other.
7. In a sign, a casing having a sign display portion, an endless belt of greater length than the display portion and adapted to be moved past the display portion, a chamber for storing the portion of the belt not being displayed, a plurality of rollers for pulling the belt over the display portion continuously and between which the belt passes, and guide means having an end terminating adjacent the point where the belt passes from between said rollers for directing the belt into the storage chamber.
8. In a sign, a casing having a sign display portion, an endless belt of greater length than the display portion and adapted to be moved past the display portion, a chamber for storing the portion of the belt not being displayed, a plurality of rollers for pulling the belt over the display portion continuously and between which the belt passes, and a stationary curved guide member having an end terminating directly adjacent the point where the belt passes from between said rollers for directing the belt into the storage chamber.
9. In a sign, a casing having a sign display portion, an endless belt of greater length than the display portion and adapted to be moved past the display portion, a chamber for storing the portion of the belt not being displayed, a roller for pulling the belt over the display portion, and a guide member having an end portion arranged tangentially with respect to said roller and terminating adjacent the point where the belt leaves said roller to direct the belt into said chamber.
